UNITED STATES PATENT OFFICE.

FREDERICK M. LASERSON, OF NEW YORK, N. Y.

PERFORATING-MACHINE.

1,346,217.

Specification of Letters Patent.

Patented July 13, 1920.

Application filed April 12, 1919. Serial No. 289,661.

To all whom it may concern:

Be it known that I, FREDERICK M. LASERSON, a citizen of Great Britain, resident of New York city, in the county of New York and State of New York, have invented certain new and useful Improvements in Perforating-Machines, of which the following is a specification.

This invention relates to perforating machines. The object of the invention is to provide a novel and practical portable machine for perforating a plurality of layers of cloth, when such perforations are desired for marking purposes in the making of garments. Other objects will appear as this specification proceeds. Accordingly the invention is embodied in a perforating machine as hereinafter described and as illustrated in the accompanying drawing in which—

Figure 1 is a front view of a perforating machine embodying my invention.

Fig. 2 is a side view of the machine, and

Fig. 3 is a plan view with parts in section 25 and parts removed.

In the drawing the reference numeral 1 denotes a substantial base, preferably circular in form and provided with a central open space for the observation of the work and the spots where the perforations are to be made. Suitably secured to the said base are two upright frame members or guides 4 and 5 which are joined at the top by a handle 6. The base carries a convenient needle guide 3. The said guides are hollow and provided with slits 7 and 8. The frames are faced with guide plates 9 and 10 forming vertical guide slots 11 and 12. 13 is an electric motor suspended in a yoke comprising the upper bearing member 14, the lower bearing member 15 and the yoke rods 16, 16 by means of which the said bearing members are joined.

The upper bearing member has a stud 17 adapted to move in the guide slot 12. The lower member 15 has a similar, but longer, stud 18 which slides in the guide slot 12 and to which stud 18 the lower end of a spring 19 is attached. The upper end of the spring 50 is attached to a stud 20 which is part of the handle 6.

The bearing members 14 and 15 are also provided with studs 21 and 22 which extend through and slide in the guide slot 11. 55 Within the frame member 5, the said two studs carry a rack frame 23 to which is se-

cured a rack 24. A spring 25 is attached to the rack frame at 26 and the upper end of the spring is attached to a stud 27 in the handle 6. The handle 6 and the studs 20 and 27 are preferably assembled into one piece with the plates 28, 28 which are screwed to the frames 4 and 5 and which form upper stops for the studs 17 and 21 as will be understood.

60 The rack 24 is engaged by a pinion 30 fast on a shaft 31 which extends outside the frame and carries an operating handle 32. 33 is a spring coiled around the shaft of the pinion and which is wound up when the shaft is rotated to prevent too rapid or careless operation. A pointer 34 is carried by the motor yoke and moves along a scale 35. 36 is a switch for starting and stopping the motor and 37 is a plug for attachment to a lamp socket. 38 is a needle attached to the motor to be driven thereby.

65 In operation the machine is placed on top of the layers of cloth and the needle registered with the mark on the cloth where the perforation is desired. The motor is started and the operator then turns the handle 32, whereby the motor is lowered and the needle driven into the cloth, perforating it. In order to prevent breakage of the needle, the 70 thicknesses of cloth may be measured and by means of the pointer and scale, the operator may accurately observe the extent to which the needle has penetrated the cloth and is able to stop the operation when all the 75 layers have been perforated.

75 The needle is moved with an even steady motion and pressure as the pinion is rotated and against the tension of the springs 19 and 25. When the perforation is finished 80 the motor is raised and kept in the upper position by the said springs.

85 A perforating machine constructed in accordance with this invention possesses several advantages. It is substantial and relatively heavy so as to keep its position on the cloth, yet it is at the same time easily carried about and the operator may safely grasp the handle 6 without danger of touching the motor.

90 The upright frame guide members besides insuring even steady motion of the motor up and down form protecting elements for the mechanism of the machine. The work is easily observable through the base, and the needle may be lowered gently down upon the cloth in order to obtain perfect registry with

the marks indicating where perforations are to be made.

While I have illustrated the preferred form of the invention it will be understood that I do not intend to limit myself to the exact disclosure herein, but that changes in the detailed form of the construction may be made without departing from the principle of the invention and the scope of the 10 appended claims.

I claim:

1. The combination of a circular base having a central opening, hollow upright frame members supported on said base, a handle 15 for joining the upper ends of said frame members, a yoke suspended from within the latter, guiding means on said frame members for the said yoke, a motor supported in the latter, a needle carried by said motor, a 20 needle guide secured to the said base and means for raising and lowering the yoke and motor.

2. The combination of a circular base having a central opening, two opposed hollow 25 frame members secured to said base and provided with vertical slits in their opposed faces, a motor, supporting means therefor, guiding members secured to the said supporting means and adapted to move in the 30 said slits, means within said hollow frames

for suspending the said yoke from the frames, a rack secured to the said yoke, a pinion in engagement with said rack, a shaft for rotating said pinion, to raise and lower the motor, a needle carried by the latter and 35 a needle guide secured to the said base.

3. The combination of a circular base, hollow frame members secured thereto, a yoke, guiding means on said yoke extending into the said frame members, springs in the latter attached to the said yoke for maintaining it in raised position, means for raising and lowering the said yoke, a motor in the same, a needle carried by the said motor and a needle guide secured to the said base. 40

4. The combination of a circular base, hollow upright frame members supported on said base in diametrically opposite relationship, a yoke, a motor mounted in the same, a needle carried by said motor, means for guiding said yoke and motor in the said frames, springs in the latter for normally maintaining said yoke and motor in upper raised position, means for raising and lowering said motor and a handle secured to the said frame 50 members. 55

Signed at New York, in the county of New York and State of New York, this 8th day of April, A. D. 1919.

FREDERICK M. LASERSON.
